E. B. Desjardins
ATTORNEY.

UNITED STATES PATENT OFFICE.

WALTER G. ARMSTRONG, OF BRIDGEPORT, CONNECTICUT, ASSIGNOR TO THE AMERICAN TUBE & STAMPING COMPANY, OF BRIDGEPORT, CONNECTICUT, A CORPORATION OF CONNECTICUT.

LIFTING JACK.

Application filed March 2, 1922. Serial No. 540,494.

To all whom it may concern:

Be it known that I, WALTER G. ARMSTRONG, a citizen of the United States, residing at Bridgeport, Connecticut, have invented certain new and useful Improvements in Lifting Jacks, of which I declare the following to be a full, clear, and exact description.

My invention relates to improvements in lifting jacks and has to do, more particularly, with lifting jacks which are adapted to be manufactured of pressed metal. This application is a continuation, in part, of my pending application for lifting jacks, Serial No. 502,731, filed Sept. 23rd, 1921.

In my pending applications, Serial No. 497,508, filed Sept. 1st, 1921, and Serial No. 502,731, filed Sept. 23rd, 1921, I have described and claimed lifting jacks of this type and the leading object of my present invention is to improve upon the constructions of said applications by simplifying the construction of the jack and reducing the number of parts. A further object of my invention is to provide a better and more effective spring action for actuating the pawls.

Further objects, and objects relating to details and economies of operation and construction, will definitely appear from the detailed description to follow. I accomplish the objects of my invention, in one instance, by the devices and means described in the following specification. My invention is clearly defined and pointed out in the appended claims. A structure constituting a preferred embodiment of my invention is illustrated in the accompanying drawings, forming a part of this specification, in which:

Fig. 1 is a side elevation of my improved jack, the operating mechanism being shown in dotted lines.

Fig. 2 is a sectional view on an enlarged scale through the upper part of the jack, showing the spring set for lowering movement.

Fig. 3 is a perspective view of one of the pressed metal pawls used in this jack, and

Fig. 4 is a sectional view similar to Fig. 2 of a modified construction, showing the spring set for raising.

In the drawings, the same reference numerals refer to the same parts throughout the several views.

The form of lifting jack disclosed in my pending applications, comprises a casing, a rack slidably mounted in the casing, an operating lever pivoted in the casing, and a pair of pawls adapted to engage the teeth of the rack. One of these pawls, the lifting pawl, is pivoted on the inner end of the operating lever and the other, the holding pawl, is pivoted on a pivot fixed in the casing. A spring is provided, the ends of which extend through perforations in the back walls of the pawls and the action of the jack is reversed by shifting the center of the spring from one side to the other of a straight line connecting said perforations. When the center of the spring is nearer the rack than the ends of the spring, said ends yieldingly force the pawls into engagement with the rack and the parts are in raising position. When the center of the spring is further from the rack than the ends, said ends tend to withdraw the pawls and the parts are in position for lowering movement. In said construction, the shifting of the spring is effected by a pivoted reversing lever and a link connecting a central part of the spring with said reversing lever.

My present invention consists in eliminating the link and using a specially formed spring, the central portions of which extend rearwardly and connect directly to the reversing lever. One important feature of my present invention consists in a special, double-armed spring connected directly to the reversing lever. Each arm of the spring may be of right-angled formation so that the portions which take the place of the link, used in my prior constructions, are a part of the spring arms and the effective length of the spring arms is correspondingly increased.

In Figs. 1 and 2, I have shown a jack construction embodying my present invention. This construction includes the pressed metal casing, 10, which has a longitudinally extending channel formed therein and the rearwardly extending portions, 11, forming a housing for the operating mechanism. The lateral flanges, 12, at the

lower end of the casing are welded to the base plate, 13. I provide a pair of side-plates, 14, which are welded to the sides of casing, 10, and which have the feet, 16, welded to the base-plate. These side-plates 5 may be pressed inwardly, at 15, to lie against the portions, 11, of the casing.

The channel-shaped rack, 17, is slidably mounted in the channel of the casing and 10 has a plurality of teeth, 18, struck out from its base. A head, 19, is mounted on the upper end of said rack. A reinforcing collar, 20, is mounted on the upper end of the casing and has a tongue, 21, which extends 15 within the channel of the rack and prevents dust and dirt from entering the interior of the casing.

A retaining pawl is pivoted in the casing on the pin, 22. Since the retaining and lifting pawls are identical, we shall use the same reference numerals in describing them. 20 Each of these pawls comprises the parallel, spaced side walls, 23, connected by a front wall, 24, the latter having a slot, 25, formed 25 centrally therein. A tongue, 26, is struck laterally from the rear edge of one side wall and forms a sort of bridge extending between the rear edges of the side walls, 23, and keeping them spaced correctly. This 30 ear, 26, is perforated, at 27, to provide a bearing for one end of the spring. Cam surfaces, 28, are formed on the rear edges of the side walls for a purpose to be described hereinafter.

35 The operating lever, 29, has its rear end formed into a socket, 30, to receive the handle, 31. This lever is pivoted in the casing on the pin, 32, and the forward end, 33, of the lever, which extends into the casing, 40 carries a pivot pin, 34, on which the lifting pawl is pivoted. The end, 33, of the lever extends between the side walls, 23, of the lifting pawl. The casing has a cam surface, 43, which cooperates with the back of the 45 lifting pawl, as will be more fully set forth hereinafter.

A wire spring of special double-armed form is provided for actuating the pawls. 50 Each arm of this spring is of substantially right angle form, as shown in Fig. 2, consisting of the rearwardly extending portion, 35, and the vertically extending free end, 36. The central portion of the spring, at the rear ends of the portions, 35, is bent to 55 form the loop, 37, which engages the pin, 38, on the reversing lever, 39. The free ends of the spring extend through the perforations, 27, of the lifting and retaining pawls, 60 respectively, and bear against the ears, 26, at said points. The reversing lever, 39, is U-shaped and has one leg extending into the casing and pivotally connected with the rear 65 end of the spring by the loop, 37; and the other leg extending along the outside of the casing and terminating in the finger grip,

41. The reversing lever is pivoted on the casing on the pin, 40. The outer leg of the reversing lever engages the stop lug, 42, pressed out from the side wall of the portion, 11, of the casing. 70

The construction shown in Fig. 4 is identical with that just described, except for the formation of the spring. In this modified construction, the spring, 44, has its central portion bent or twisted to form a rearwardly 75 extending shank, 45, having an eye, 46, which receives the pin, 38, by which the shank, 45, is pivotally connected to the inner leg of the reversing lever, 39. The free 80 ends of the spring, 44, work in the perforations, 27, of the pawls, just as in the form previously described.

From the description of the parts given above, the operation of my improved lifting jack should be readily understood. In 85 Fig. 1, the parts are shown in the lifting position so that, when the handle, 31, is worked up and down, the rack, 17, will be raised to lift the load engaged by head, 19. In this position, the adjacent ends of the vertically 90 extending portions, 36, of the spring are nearer the rack than the ends engaging the pawls and such free ends, engaging the pawls at the perforations, 27, force the pawls toward the rack. As the handle, 31, is depressed, the lifting pawl is raised carrying the rack with it, while the retaining pawl rides over a tooth of the rack and snaps into engagement with the next lower tooth. 95 When the handle, 31, is raised, the rack is held from dropping by the retaining pawl, while the lifting pawl moves down, riding over a tooth of the rack and springing into engagement with the next lower tooth. This 100 operation is repeated at each stroke of the handle. When it is wished to lower the load, the reversing lever, 39, is shifted to the position shown in Fig. 2. This shifts the spring so that the adjacent ends of the vertically 105 extending portions, 36, of the spring 110 are further from the rack than the free ends of such portions and, consequently, the spring tends to move the pawls away from the rack. This tendency is ineffective as long as there is a load on the pawl. In Fig. 2, the handle is lowered and the spring arm has withdrawn the retaining pawl from the 115 rack. As the handle, 31, is raised the lifting pawl is lowered and the load causes the rack to drop with said pawl. Toward the 120 end of the upstroke of the handle, the lower end of the lifting pawl engages the cam surfaces, 28, on the back of the retaining pawl and forces the latter into engagement with the rack, so that the downward movement 125 of the rack is halted and the load is shifted from the lifting pawl to the retaining pawl. When this takes place, the spring arm withdraws the lifting pawl from engagement 130 with the rack. Now, the handle, 31, is de-

pressed and the lifting pawl, which is clear of the rack, moves upwardly. Toward the end of this movement, the back of the lifting pawl engages the cam surface, 43, of the casing and is forced by it into engagement with the rack so that, as its upward movement continues, it takes the load from the retaining pawl and the spring arm withdraws the latter from engagement with the rack. This 10 operation is repeated at each stroke of the handle. The operation of the modified construction shown in Fig. 4 is the same.

The improved construction disclosed herein results in a simplification of the jack since 15 the spring is connected directly to the reversing lever and no link is used as in my prior constructions. Furthermore, the spring is anchored at the loop, 37, and both the rearwardly extending portion, 35, and 20 the vertically extending portion, 36, constitute a part of the spring arm, so that I have a longer spring arm and, consequently, a better and more effective spring action. It will be noted that the portions, 35, flex with 25 respect to each other with a scissors-like action, when the spring is in action and that the entire spring arm from the loop, 37, to the free end of the spring flexes under pressure. The form shown in Fig. 4 results in 30 a simplification of construction by eliminating the link but the spring arm is not so long and the spring is not so effective as the preferred form.

I am aware that the construction described herein may be altered considerably 35 without departing from the spirit of my invention and, therefore, I claim my invention broadly, as indicated by the appended claims.

40 Having thus described my invention, what I claim as new and useful and desire to secure by Letters Patent is:—

1. A device of the class described comprising a casing, a rack slidably mounted therein, an operating lever pivoted on said casing, a lifting pawl carried by said lever and engaging said rack, a retaining pawl pivoted on said casing and engaging said rack, a spring having its ends engaging said 45 pawls and its central portion extending rearwardly, and a reversing lever directly connected to said rearwardly extending central portion.

2. A device of the class described comprising a casing, a rack slidably mounted therein, an operating lever pivoted on said casing, a lifting pawl carried by said lever and engaging said rack, a retaining pawl pivoted on said casing and engaging said rack, a spring having its ends engaging said pawls and its central portion formed into a loop, and a reversing lever pivoted on the casing 50 and having a pin engaging in said loop.

3. A device of the class described comprising a casing, a rack slidably mounted there-

in, an operating lever pivoted on said casing, a lifting pawl carried by said lever and engaging said rack, a retaining pawl pivoted on said casing and engaging said rack, a spring having a central loop and a pair 70 of spring arms extending first forwardly and then vertically from said loop with the free ends of said arms engaging said pawls, and a reversing lever pivotally connected to said central loop.

4. A device of the class described comprising a casing, a rack slidably mounted therein, an operating lever pivoted on said casing, a lifting pawl carried by said lever and engaging said rack, a retaining pawl pivoted on said casing and engaging said rack, a spring having a pair of angular spring arms the free ends of which engage said 80 pawls, and a reversing lever connected directly to said spring at the junction of said 85 arms.

5. A device of the class described comprising a casing, a rack slidably mounted therein, an operating lever pivoted on said casing, a lifting pawl carried by said lever and engaging said rack, a retaining pawl pivoted on said casing and engaging said rack, a spring having a central loop and a pair of right-angled spring arms each extending forwardly from said loop and 90 thence vertically, and a reversing lever pivotally connected to said central loop.

6. A device of the class described comprising a casing, a rack slidably mounted therein, an operating lever pivoted on said casing, a lifting pawl carried by said lever and engaging said rack, a retaining pawl pivoted on said casing and engaging said rack, a spring having a pair of right-angled 100 spring arms each including a horizontal and a vertical portion, the outer ends of said vertical portions engaging said pawls and said arms crossing each other adjacent the inner ends of said vertical portions, and a reversing lever connected to the rear ends of the 110 horizontal portions of said spring arms.

7. A device of the class described comprising a casing, a load-lifting member movable therein, an operating lever pivoted on said casing, a lifting pawl carried by said 115 lever and engaging said member, a retaining pawl pivoted on said casing and engaging said member, a spring having a pair of angular spring arms the free ends of which engage said pawls, and a reversing lever 120 directly connected to said spring arms.

8. A device of the class described comprising a casing, a rack slidably mounted therein, an operating lever pivoted on the casing, a lifting pawl carried by the lever 125 and engaging the rack, a retaining pawl pivoted on said casing and engaging said rack, a spring having its ends engaging said pawls and its central portion formed into a shank extending laterally from the portions of the 130

spring which engage the pawls, and a reversing lever pivotally connected to said shank.

9. A device of the class described comprising a casing, a rack slidably mounted therein, an operating lever pivoted on the casing, a lifting pawl carried by said lever and engaging said rack, a retaining pawl pivoted on said casing and engaging said rack, a

spring having its ends engaging said pawls 10 and its central portion twisted to form a rearwardly extending shank, and a reversing lever directly connected to the rear end of said shank.

In testimony whereof, I affix my signature. 15

WALTER G. ARMSTRONG.
